UNITED STATES PATENT OFFICE.

ROBERT HEATON TAYLOR, OF SHEFFIELD, COUNTY OF YORK, ENGLAND.

SPRING-PACKING FOR PISTONS AND OTHER ANALOGOUS USES.

SPECIFICATION forming part of Letters Patent No. 313,251, dated March 3, 1885.

Application filed July 24, 1884. (No model.) Patented in England January 28, 1884, No. 2,252; in France June 27, 1884, No. 163,002, and in Germany June 29, 1884, No. 30,178.

To all whom it may concern:

Be it known that I, ROBERT HEATON TAYLOR, a subject of the Queen of Great Britain and Ireland, and a resident of Sheffield, in the county of York, England, engineer, have invented certain Improvements in Spring-Packing for Pistons and other Analogous Uses, (for which I have obtained a British patent, No. 2,252, dated January 28, 1884; German Patent No. 30,178, dated June 29, 1884, and French Patent No. 163,002, June 27, 1884,) of which the following is a specification.

This invention relates to certain improvements in or applicable to the manufacture or 15 construction and improved formation of spring-packing for expanding or distending the rings of pistons and analogous parts of steam-engines, air-pumps, and other apparatus.

20 The especial object of the invention is to produce such packing of an improved formation and of considerable strength, great lightness, and perfect evenness of bearing at all parts in its radial and vertical expansive action 25 in distending and separating the piston-rings and forming a perfectly steam-tight joint with a minimum of friction.

The piston-block and its covers may be of any usual formation, and may be bolted or 30 otherwise secured together in any usual manner, and it has, therefore, not been considered necessary to illustrate such parts on the accompanying drawings.

On the accompanying drawings, Figure 1 35 represents a sectional elevation of the rings of a piston with the improved packing in position between them. Figs. 2, 3, and 4 represent similar views, respectively, of one of the piston-rings and of one of the spring- 40 rings and the spring composing such improved packing. Fig. 5 represents a plan view of the parts shown in Fig. 1. Fig. 6 represents a similar view to that of Fig. 1, but 45 illustrates a modified formation of the packing. Fig. 7 represents in section one of the spring-rings illustrated in Fig. 6. Fig. 8 represents a further modified formation of the spring; and Fig. 9 represents in plan view one-half of the 50 spring-ring and one-half of the spring, respectively, illustrated in Figs. 7 and 8.

The piston-rings 1 may be of any usual formation, each being, however, made with an internal flange, 2, and preferably with a squared inner seating, 3. The openings in the rings may be fitted with gluts 4 in any usual manner. 55

The improved packing comprises a duplicate arrangement of spring-rings 5, which are seated within the said seatings of the piston-rings, and an intermediate spring, 6, which 60 gives the radial and vertical expansive action to the said spring-rings, which act directly upon the piston-rings. The spring-rings are made of any suitable hard elastic metal—such as cast iron, steel, or gun-metal—and of such a conformation as will allow of their being fitted within the said seatings of the piston-rings, and they are formed at equal or irregular distances apart, with inner projecting ribs or bars, 7, arranged radially with their faces against which 65 the spring bears at an angle, preferably, of forty-five degrees, as illustrated in Figs. 1, 3, and 5; or, as illustrated in Figs. 6, 7, and 9, the ribs or bars 7 may be formed externally of the spring-rings, so as to have their bearings 70 in the said seatings of the piston-rings, the plane part of each spring-ring then being angularly-arranged in like manner, as hereinbefore referred to, for the spring to bear against. 75

When spring-rings of any modification of 80 this formation are seated within the piston-rings, their inner bearing-surfaces thus form an angle of ninety degrees; but I desire it should be understood that I do not limit myself to this precise angle, which is more advisable 85 than it is arbitrary, and that the angle formed by such bearing-surfaces may either be somewhat more obtuse or acute than that of ninety degrees.

The spring is preferably made of steel, either 90 cast or rolled, or tempered, if required, and of a right-angled formation as regards its external edge, or of such an angular formation as that it will fit between the said spring-rings, as shown in Fig. 6, in such a manner as that it 95 will give an equal expansion radially and vertically to both of such spring-rings.

It is preferred to make the springs with the back or inner circumference hollowed, and of a greater sectional strength or thickness at the 100

part opposite the opening of the spring than at the opening; or the springs may be formed with transverse ribs or stays 8 at parts, as shown in Figs. 1 and 4; or slots 9 may be punched in the spring at suitable distances apart, as shown in Figs. 8 and 9, to equalize the strength of the spring.

The spring is made of a slightly larger diameter than that of the spring-rings, and the diameter of these is made slightly larger than that of the piston-rings, so that when the springs are compressed within the spring-rings, and the latter within the piston-rings, and the piston-cover is bolted down, a sufficient and even distention of the piston-rings is effected, insuring a perfectly tight and elastic joint, and sufficient resiliency is left to insure the continuance of the same action be-

tween the parts as the piston-rings become worn.

I am aware of Goodfellow's British Patent No. 7,912 of 1838, and do not wish to claim anything therein described; but

I claim as my invention—

In a spring-packing, the combination of the 25 double-acting spring 6, having opposing angular bearing-faces, with corresponding spring-rings, 5, having ribs 7, substantially as and for the purpose set forth.

In testimony whereof I have signed my name 30 to this specification in the presence of two subscribing witnesses.

R. H. TAYLOR.
